UNITED STATES PATENT OFFICE

FREDERICK E. STRUVE, OF PHILADELPHIA, PENNSYLVANIA, ASSIGNOR TO APEX HOSIERY COMPANY, OF PHILADELPHIA, PENNSYLVANIA

FULL FASHIONED CLOCKED HOSIERY AND METHOD OF PRODUCTION

Application filed October 26, 1931. Serial No. 571,104.

This invention relates to a full fashioned clocked design of hosiery and has for its primary object the provision of a "shadow" design of clock border by an open work design.

Heretofore in the manufacture and sale of hosiery, clock lace features have been utilized and further embroidered clocks have been utilized but I am of the opinion that 10 I am the first to incorporate in a clock design, figurative panels of reinforcing material surrounded by an open work design, the marginal portion of the figurative panels having an overlapping relation with the stocking 15 web to provide thicker material at these points to produce a "shadow" effect.

As is well known in the trade, clock lace types of stockings are not very durable and have limited wear and furthermore embroidered yarn upon stocking webs considerably weakens the same. To overcome these 20 defects, others in the field have resorted to the knitting of a reinforcing thread into the stocking web in a manner to produce a 25 figurative design which lacks that degree of ornamentation demanded by the present day type of trade.

The principal object of my invention is to overcome the above objections by providing 30 a full fashioned silk stocking with a clock design that will combine the separate advantages of open work lace design and reinforced yarn clock design and further will include novel ornamental effects not characteristic of clock designs heretofore produced.

A feature of my invention resides in the simultaneous and continuous knitting of the open work design, the figurative panels and 40 a shadow producing border for the panels.

With these and other objects in view the invention will be better understood from the following detailed description taken in connection with the accompanying drawings 45 wherein:

Figure 1 is a fragmentary portion of a stocking.

Figure 2 is an enlarged view of the clock.

Figure 3 is an enlarged detail view of a 50 portion of the clock.

Figure 4 is a diagrammatic view illustrating the action of the yarn carriers.

The leg web 1 of the stocking is knitted in the usual manner utilizing a fine silk thread until a point in the formation of the stocking 55 is reached where the clock design is to be produced.

Referring to Figure 2, it will be noted that the clock design consists broadly of an open work design 2 and figurative panels 3. In 60 the production of the open work design 2 single loops are transferred to adjacent needles in a manner well known in the trade. It will be noted that the aligned arrangement of the openings of the open work design 2 is such 65 as to provide a border or boundary for the panels 3 which materially enhances the aesthetic value of the panels 3 and besides the ornamental effect of the open work design 2 in conjunction with the design of the panels 70 3 produces a composite effect not characteristic of clock designs heretofore produced.

In the construction of the figurative panels 3, I utilize a heavy reinforcing yarn or thread which is knitted in, simultaneous with the 75 loops of the stocking web. To accomplish this desired result the yarn carrier carrying the stocking web thread is selectively controlled in its travel in a manner well known in the trade and simultaneous with this action the yarn carrier for the heavier yarn is selectively controlled in its travel so that the heavier yarn will be interlocked with the light yarn of the stocking web to produce the panels 3. To enhance the beauty of the clock 80 and to more prominently bring out the outline of the panels 3, I manipulate the yarn carriers to travel in overlapping relation thereby providing a border formation 4 for the panels 3 illustrated as blocks 5. 85

Referring specifically to the diagrammatic view Figure 4, it will be noted that the light thread 6 of the stocking web in certain positions travels full across the path of travel of the heavier yarn designated by the numeral 7 to locate certain blocks 5 in position to separate the figurative panels 3. In other positions, the stocking web thread 6 has a limited distance of travel so as to only slightly overlap with relation to the travel of the 90 100

heavier yarn to produce what is known in the trade as a split lock.

By utilizing the split lock formation as shown, I produce a shadow effect around the border line of the panels 3 which produces a beautiful effect when the stocking is dyed.

I am aware of the fact that open work designs have been used before, clocks of reinforcing materials have been utilized and a split lock construction utilized in the construction of a stocking, but I am of the opinion that I am the first to arrange an open work design, a clock of reinforced material and a split lock formation in the relative arrangement illustrated so as to provide a composite effect not characteristic of clock design heretofore produced.

If desirable in practice the figurative panels 3 may be also provided with an open work design as illustrated at 8.

Due to the cooperative arrangement of the panels of reinforcing material, the reinforcing blocks of material and the openings, I am able to considerably reinforce the open work design so as to prevent the weakening of the stocking. As the open work design has a definite outlined relation with the outline of the figurative panels and the border formation has a definite relation with the marginal edge of the panels 3 and also with the open work design, it will be appreciated that I produce a harmonious arrangement that greatly adds to the aesthetic value of the stocking as a whole and therefore I do not desire to be limited in protection in any manner whatsoever except as set forth in the following claims.

What I claim is:

1. As a new article of manufacture a full fashioned clocked stocking, the clock consisting of a plurality of figurative panels formed from a knitted reinforcing thread that has a split lock connection with the thread of the stocking web to form border formations for the panels, the stocking web being provided with a plurality of openings arranged in an ornamental relation and surrounding the said figurative panels as a group.

2. As a new article of manufacture a stocking having the leg portion of silk chiffon provided with an open work figure, a clock arranged within the open work figure and consisting of a plurality of figurative panels formed from reinforcing threads that have a split lock connection with the thread forming the chiffon leg portion, said split lock connection forming blocks of reinforcement providing a border for said figurative panels.

3. The herein described method of manufacturing full fashioned clocked hosiery which consists in forming directly in the stocking web a plurality of design openings, knitting in the stocking web figurative panels of reinforcing material bounded by said design openings and arranging the loops of

the figurative panels in overlapping relation with the loops of the stocking web to provide blocks of reinforcements as a border for said figurative panels.

4. The herein described method of manufacturing full fashioned clocked hosiery which consists in knitting simultaneously and continuously an open work design in the stocking web, a figurative panel of a reinforcing thread bound by said open work design and overlapping the reinforcing thread with the thread of the stocking web to provide for the figurative panels a border of an increased thickness.

In testimony whereof I have signed this specification this 17th day of October, 1931.

FREDERICK E. STRUVE.
